Des. 189,890
Patented Mar. 14, 1961

189,890

COMBINED VACUUM BOTTLE UNIT AND HOLDER

John G. Bradshaw, 129 Newington Road, Elmwood,
Conn., and George A. Kingham, 44 Hull St., Bristol,
Conn.

Filed Apr. 28, 1960, Ser. No. 60,350

Term of patent 14 years

(Cl. D58—6)

FIG. 1

FIG. 2

FIG. 3

Fig. 1 is a perspective view of a combined vacuum bottle unit and holder showing our new design;

Fig. 2 is a top plan view thereof with the holder removed; and

Fig. 3 is a side elevational view thereof with the holder removed.

The dominant features of our design reside in the portions shown in full lines. The rear and end, not shown, is the same as the front and end, respectively, shown.

We claim:

The ornamental design for a combined vacuum bottle unit and holder, as shown and described.
